Primary Examiner — Cary M Robinson*Assistant Examiner* — Julie Marie Bailey*(74) Attorney, Agent, or Firm* — Maier & Maier, PLLC(57) **CLAIM**

The ornamental design for an ultraviolet corn lamp, as shown and described.

DESCRIPTION

FIG. 1 is a front view of an ultraviolet corn lamp, showing our design;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof; and,

FIG. 8 is another perspective view thereof.

The broken line showing in the Figures shows portions of the ultraviolet corn lamp and forms no part of the claimed design.
